US0D1094527S

(12) **United States Design Patent** (10) Patent No.: **US D1,094,527 S**
(45) Date of Patent: ** Sep. 23, 2025

(54) **GLASSES**

(71) Applicant: **HEYWIND TECHNOLOGY LIMITED**, Hong Kong (HK)

(72) Inventor: **Mimi Huang**, Fujian (CN)

(73) Assignee: **HEYWIND TECHNOLOGY LIMITED**, Hong Kong (CN)

(**) Term: **15 Years**

(21) Appl. No.: **29/991,625**

(22) Filed: **Mar. 3, 2025**

(51) LOC (15) Cl. **16-06**

(52) U.S. Cl.

USPC **D16/326**

(57) **CLAIM**

The ornamental design for a glasses, as shown and described.

DESCRIPTION

FIG. 1 is a perspective view of a glasses showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the encircled portion in FIG. 1; and,

FIG. 10 is an enlarged view of the encircled portion in FIG. 2.

The evenly dashed broken lines in the drawings show portions of the article that form no part of the claimed design. The dashed dot broken lines in the figures demarcate the enlarged views and form no part of the claimed design.

1 Claim, 10 Drawing Sheets
